(57) **CLAIM**

The ornamental design for a particle for animal litter, as shown and described.

DESCRIPTION

FIG. 1 is a perspective view of the particle for animal litter; FIG. 2 is a top view of the particle for animal litter of FIG. 1;

FIG. 3 is a bottom view of the particle for animal litter of FIG. 1;

FIG. 4 is a front elevation view of the particle for animal litter of FIG. 1;

FIG. 5 is a rear elevation view of the particle for animal litter of FIG. 1;

FIG. 6 is a left elevation view of the particle for the animal litter of FIG. 1; and,

FIG. 7 is a right elevation view of the particle for animal litter of FIG. 1.

It is to be understood that those portions of the particle shown in broken line in the accompanying figures do not constitute an integral part of the claimed design and, therefore, are disclaimed as part of the claimed design.
